UNITED STATES PATENT OFFICE

THOMAS L. CROOK, OF HICKSVILLE, OHIO

D-HANDLE FOR TOOLS

Application filed May 25, 1932. Serial No. 613,374.

This invention relates to handles for shovels, spading forks and similar implements, and particularly to such handles of the split D-type.

The object of the invention is the provision of a simple, efficient and improved handle of this character, which is reinforced at weak points by a novel application and distribution of metal parts to not only provide a strong and durable handle, but also to simplify and cheapen the cost of construction and assembly of the handle parts and to enable small pieces of scrap metal to be used for reinforcing purposes.

The invention is fully set forth in the following specification and one embodiment thereof illustrated in the accompanying drawing, in which—

Figure 1 is an elevation of a handle embodying my invention. Fig. 2 is a section thereof on the line 2—2 in Fig. 1, with a portion broken away. Fig. 3 is an enlarged fragmentary section of a handle taken on line 3—3 of Fig. 1. Fig. 4 is a similar section taken from one side edge thereof as along a line 4—4 in Fig. 2, and Fig. 5 is an end elevation of the handle grip or roll member.

Referring to the drawing, 1 designates the wooden shaft or stem carrying the shovel, or other implement, at one end and having its other or upper end portion longitudinally split or bifurcated to form the two spaced arms 2 and 3, and firmly connected thereto by a cross-pin 5 passing through an axial aperture 6 in the grip-bar and aligned apertures 7 in the shaft arms.

The grip-bar 4 has each end face cut away at 8 to provide a straight shoulder 9 there-across slightly below the aperture 6, and the projecting portion 10 of the end face thus formed is provided with a marginal edge recess 11 around its curved portion.

The inner flat side of each arm 2 and 3 is cut away or recessed at its upper end, as at 12, to adapt it to receive the projecting end portion 10 of the grip-bar and to provide a step or shoulder 13 at its lower edge for the shoulder 9 of the bar end.

The upper end of each shaft arm, 2, 3, and the connection of the grip-bar 4 and shaft 7

therewith, is reinforced by inner and outer metallic strips 14 and 15, respectively, which are adapted to be and preferably are formed from flat scrap sheet steel.

The inner strip 14 is substantially flat to fit against and conform to the flat inner face shaft-arm, and extends from the upper end edge of the arm to a distance of two or three inches below the grip-bar 4, and is provided at its upper end with an outwardly stepped or offset portion 16, which fits in and conforms to the stepped or recessed portion 12, 13, of the arm. It is thus apparent that the strip 14 forms a metallic facing for the portion of the shaft arm against which the end 60 of the grip-bar 4 abuts and at the same time provides a firm seat for the shoulder 9 of the grip-bar.

The outer strip 15 is of hood or rounded concaved form at its upper end to fit over and receive the upper end of the associated shaft arm and to seat at its edge in the edge recess 11 of the respective end of the grip-bar 4, the side edges of the hood extending down at each side substantially to the shoulder 9 of the grip-bar. The leg portion of the strip 15 is curved in cross-section to conform to the curved outer side of the shaft arm and gradually reduces in width to its free end and as best shown in Fig. 1. The edges of the inner strip 14 substantially from the stepped portion 16 downwardly, and the edges of the outer strip 15 substantially from the lower edges of the hood portion thereof, are turned slightly inward to adapt them to be imbedded in the respective surfaces of the shaft arms and thus prevent sharp edges of the strips from being exposed where they might cause injury to the hands of a person handling the implement.

The pin 5 passes through the strips 14 and 15 of both arms and is headed at the outer sides of the strips, thereby serving to retain all of the parts in strong and rigid assembled relation. The lower ends of the strips 14 and 15 of each pair are secured together and firmly held to the shaft arm by a rivet 17 extended through the arm.

It is found in practice that the manner shown and described for assembling and

mounting the handle parts, provides not only a strong and rigid construction, but also an inexpensive one. It is also found important in practice to provide the metal spacing member constituted by the strips 14 between the ends of the grip handle and the respective shaft arms, particularly in combination with the stepped feature, as it adds materially to the strength and wearing quality of the handle and tends to maintain the grip-bar tight with respect to the shaft arms more efficiently than where this spacing feature is not present.

I wish it understood that my invention is not limited to any specific construction, arrangement or form of the parts, as it is capable of numerous modifications and changes without departing from the spirit of the claim.

Having thus described my invention, what I claim as new, and desire to secure by United States Letters Patent, is:

A D-handle comprising a wooden shaft having its upper end bifurcated to form diverging arms, said arms being substantially half round in cross-section with their flat faces disposed inward, a grip-bar disposed between the outer ends of the arms, the ends of the grip-bar and the respective aligned inner face portions of the arms having complementary stepped surfaces forming transverse shouldered engagement one with the other at a point below the grip-bar axis, inner and outer metallic reinforcing strips for the outer end portions of the arms, each inner strip having its outer end disposed between the opposed portions of the grip-bar and respective arms and conforming to the stepped form thereof, and each outer strip having its outer end hooded over the end of the respective arm and in coaxing engagement with the respective top and side end edge portion of the grip-bar, a pin extending coaxially through the grip-bar and through the aligned portions of the arms and reinforcing strips to rigidly retain the several parts in assembled relation, and rivet means securing the lower end of the strips to the respective arm.

In testimony whereof I have hereunto signed my name to this specification.

THOMAS L. CROOK.
